UNITED STATES PATENT OFFICE

2,493,468

HOPPER DOOR FOR RAILWAY CARS

James S. Swann, Homewood, Ill., assignor to
Standard Railway Equipment Manufacturing
Company, Chicago, Ill., a corporation of Delaware

Application August 2, 1946, Serial No. 688,067

5 Claims. (Cl. 105—280)

1

This invention relates to railway freight cars and more particularly to cars of the dumping or drop bottom type, such as hopper cars, gondola cars, or the like, having a door forming a part of the load retaining means, said door being provided with hinges along one edge so as to be capable of being dropped or swung open to discharge the load. Any acceptable means of raising the door to closed position, and any means for locking and releasing the door may be used with the invention.

An object of the invention is to provide a hopper door, preferably formed from a flat metallic plate, and supported from the railway car by spaced hinges and a spreader and which is provided with a continuous peripheral stiffening flange and a plurality of panels formed therewithin and positioned to cooperate with each other and the peripheral flange in combination with the hinge straps so that the tendency of the door to bend or deflect under load is resisted by a plurality of webs of the panels and the peripheral flange. In other words, bending on any straight line crossing the door is resisted by a plurality of webs formed in the door.

Another object of the invention is to provide a freight car drop door having corrugations and/or panels therein so constructed and arranged that the webs of said panels or corrugations form a large number of Z-shaped stiffening ribs extending at substantially right angles to each other through the door.

A further object of the invention is to provide such a corrugated or paneled drop door so constructed as to provide certain areas upon the door in the same plane to thereby provide flat bearing surfaces for the attachment thereto of the door hinges and spreader, thus eliminating the necessity of designing special spreader extensions for locking mechanism, and the hinges are interchangeable for any type of car. Furthermore, such construction of door provides a marginal area all in one plane for flush engagement with the door frame.

In the drawings:

Figure 1 shows a door in vertical position embodying the invention and applied to the door frame of a railway hopper car.

Figure 2 is a section on the line 2—2 of Figure 1.

Figure 3 is a section on the line 3—3 of Figure 1 with the door closed.

Figure 4 is an end elevation of Figure 1 showing the door in closed position and associated parts of the car.

Figure 5 is a section through the door and

2

hinge and section modulus curve and bending moment curve of constant strength.

The usual car parts associated with a hopper car door are shown in the drawings, such as the hopper bottom sheet 10, the hopper cross ridge sheet 11, hopper inside sheet 12, hopper outside sheet 13, hopper stiffener 14, hinge support angle 15, side wall 16, and lower side chord 17. The hopper stiffener 14, which is shown as of angle 10 form, extends across the bottom of the door and is secured by rivets 18 to rolled angle 19, the base flange of which occurs in the same plane as the outer edges of the hinge support angle 15 and the side sections 19' and 19'', thus forming a frame 15 for the hopper opening. Stiffener 14 and angle 19 are also secured to the hopper bottom sheet 10.

The door for closing said opening is preferably formed by hot pressing from sheet metal and comprises a metallic plate 20 having a corrugation 21 pressed in the outer margins of the plate from the original plane thereof and extending continuously about the door, leaving an outwardly extending stiffening flange 22 entirely around the perimeter of the door. At the upper 25 corners of the door, said corrugation 21 is widened into two substantially rectangular areas, shown as 23—23, thus providing flat bases for the attachment thereto of the hinge straps 24, the bolts of which hinges are secured to the hinge support 30 angle 15.

Substantially centrally of the door there is pressed from the original plane of the plate to the plane of said areas 23 a substantially inverted T-shaped panel 25, thereby leaving a 35 substantially similarly shaped T-shaped corrugation 26 in the original plane of the plate between the corrugations 21 and the panel 25. The bar part 27 of corrugation 25, which is in the same plane as areas 23—23, forms a flat base for the attachment thereto of the Z-shaped spreader 28 of the door. The stem 29 of the T-shaped corrugation extends between said areas 23—23, and said areas 23—23 form corner gussets to assist in holding said door in square and plane. 40

Spreader 28 extends across the car and is similarly attached to the door of the opposite hopper and said part 27 being in the same plane as corrugation 21 eliminates the necessity of designing special spreader extensions for locking mechanism.

In plan view, as shown in Figure 1, the door is provided with a T-shaped panel 26 in the original plane of the plate, and the similar T-shaped smaller panel 25 within said panel 26 but pressed from the plane of the plate, and with the mar-

ginal corrugation 21 (forming a peripheral flange) entirely about said panels adjacent the outer edges of said plate. Thus it is apparent from the sectional views 2 and 3 that the sides of corrugations 21 and panel 25 form a large number of Z-shaped stiffening ribs through the door in both directions.

In the drawing Figure 5, line 30 shows the section modulii (above the base line 31) of the various sections between the hinge pin line 32 and the lower margin line 33 of the door. Line 34 shows the bending moments required at the various sections to support an equally distributed load on the door, and line 65 shows the neutral axis of the supporting spreader bar 28.

As the door itself does not extend to and is not supported by the hinge pins, the hinge straps 24 are designed to continue the beam from the upper margin 35 of the door to the hinge pins. The shaded portion 36 of the diagram Figure 5 shows the minimum required strength added by the hinge strap, which, of course, will vary with different types of hinges.

The sagging or deflection of the door anywhere between the line 38 and 39 (and substantially parallel thereto) is resisted by four webs (40-40, 41-41 and the hinge straps). Such sagging or deflection between lines 39 and 42 is resisted by six webs 40-40, 43-43 and 44-44. Such sagging or deflection between the line 42 and the lower margin of the door is resisted by four webs (40-40 and 43-43) which is sufficient, as shown by the diagram Figure 5.

The sagging or deflecting of the door on lines parallel to the side margins of the door anywhere between lines 50 and 51 is resisted by six webs 52, 53, 54, 55, 56 and 57. Such sagging or deflecting between lines 51 and 58 or 50 and 59 is resisted by four webs (52, 53, 54 and 55) which is sufficient to support the overhanging load between lines 50 or 51 and the adjacent side margin of the door. Such deflection or sagging between lines 58 or 59 and the adjacent edge of the door is resisted by two webs 52 and 53.

The drooping of the upper corners of the door between lines 60 and the corner of the door is resisted by webs 40 and 52 and the hinge straps 24.

The drooping of the lower corners of the door between lines 61 and the corner of the door is resisted by webs 40, 43, 55 and 53.

From the foregoing it will be apparent that any deflection of the door on any straight line crossing the door will be resisted by a plurality of stiffening webs.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A dump car door comprising a metallic plate having a continuous corrugation pressed from the plane of the plate and extending about the sides and top and bottom of the plate adjacent the margins thereof, said corrugation being of increased area at opposite corners of one side of said plate to provide sufficient area for attaching hinges thereto, a substantially T-shaped panel pressed from the plane of the plate within and to the plane of said corrugation and forming an attaching surface across the door for a spreader, whereby the walls of said corrugation

and panel form a plurality of Z-shaped stiffeners through the door extending at angles to each other, the stem of said T-shaped panel extending between said increased areas of said corrugation.

2. A door adapted to be hinged to a car above a hopper discharge opening therein for opening and closing said opening, said door comprising a metallic plate having a continuous corrugation extending about the sides and top and bottom of the plate and being of sufficient area at the upper corners of the plate to provide attaching surfaces for door hinges, and a T-shaped panel within said continuous corrugation with the flange portion providing an attaching surface for a spreader and the stem portion extending between said upper corners of the plate, whereby the walls of said panel and corrugation form a plurality of Z-shaped stiffeners extending transversely and longitudinally of said door.

3. A door adapted to be hinged to a car above a hopper discharge opening therein for opening and closing said opening, said door comprising a metallic plate having a marginal flange adapted to overlap the walls of the hoppers, a continuous corrugation extending about the sides and top and bottom of the plate adjacent the margins thereof and being of sufficient area at the upper corners of the plate to provide attaching surfaces for door hinges, and a T-shaped panel within said continuous corrugation, the flange portion of said T-shaped panel providing an attaching surface for a spreader and the stem portion of said panel extending toward the upper edge of said plate between said hinge attaching surfaces, whereby the walls of said panel and corrugation form a plurality of Z-shaped stiffeners extending transversely and longitudinally of said door.

4. A door for forming a load retaining means for a hopper of a railway car and adapted to be supported from said car by spaced hinges and a spreader adjacent to and spaced from the lower edge of the door; said door provided with a T-shaped panel, pressed in the central portion of the plate, a corrugation extending continuously about the door, pressed in the margin of said door in the direction of and to the plane of said panel, spaced therefrom, and forming a groove for the reception of the hopper walls; said corrugation being enlarged at the corners opposite the narrower portion of said panel to provide corner gussets and flat portions of the door for attachment of hinge straps to hinge said door to said hopper, so that the space between said panel and said corrugation conforms to the shape of said panel and occurs in the original plane of the plate.

5. A door for forming a load retaining means for a hopper of a railway car and adapted to be supported from said car by spaced hinges, said door formed from a single plate of material and provided with a T-shaped panel pressed in the central portion of the plate, a corrugation extending continuously about the door pressed in the margin of the door in the direction of and to the plane of said panel and spaced therefrom forming a groove for the reception of the edges of the hopper walls, said corrugation being enlarged at the corners to provide corner gussets with the stem portion of said T-shaped panel extending therebetween so that the space between said panel and said corrugation conforms to the shape of the panel and occurs in the original plane of the plate, thereby providing a plurality of stiffening ribs of Z-section on any line through the door

to resist forces imposed on said door by a plastic
lading.
